ROLL WRAPPING APPARATUS

Harvey H. Way, Wildwood Heights, near Powell River, British Columbia, Canada, assignor to Powell River Company Limited, Vancouver, British Columbia, Canada

Application April 23, 1951, Serial No. 222,376

37 Claims. (Cl. 53—98)

1

This invention relates to apparatus for mechanically applying wrapper bands and/or end caps to rolls of paper or any other material over a wide range of diameters and lengths.

An object of the present invention is the provision of means for mechanically applying wrapper bands to rolls, such as paper rolls, whereby the latter are uniformly wrapped in a minimum of time.

Another object is the provision of means for quickly and easily applying end caps to rolls, such as paper rolls without the necessity of manual labor other than keeping the apparatus supplied with caps and, if necessary, glue.

Under the present generally adopted wrapping procedure, a large sheet of wrapping paper somewhat longer than the length of the paper roll is wrapped over the entire roll and glued in place. Due to the wrapper being longer than the roll, it projects beyond both ends of the roll. A circular sheet of wrapping paper slightly smaller in diameter than the roll is placed over the roll end and the projecting ends of the wrapper folded down over it. It is then usual to apply by hand glued bands of wrapping paper around the circumference of the roll at either end which project beyond the ends of the roll. The number of bands so applied varies with different wrapping requirements and different numbers of bands may be applied to opposite ends of the same roll. In some instances one or more bands are wrapped around the circumference of the roll at points intermediately situated between the two ends. This practice is general where two or more rolls are wrapped in the same wrapper. After the bands have been applied, the portion of the end bands which project beyond the end of the roll are folded inwardly over the roll ends or crimped by hand. The roll is then transferred to a capping machine by manpower. The roll, lying on its side, and situated between two movable platens, the surface of which may be heated or not, depending upon the type of glue used in this particular operation. Discs of wrapping paper the approximate size of the ends of the roll are covered with glue on one side and attached to the face of the platens by means of a pin, clip, or other device. Both of these operations are carried out by hand. The platens carrying the caps move inwardly and exert pressure on the ends of the roll, and after this pressure has been maintained for a predetermined interval until the glue has bonded, the platens are retracted and the roll discharged.

While this machine is particularly designed for

2

handling rolls of paper, and is so described herein, it is to be understood that it may be used for handling rolls of any other material requiring wrapper bands and/or end caps.

5 This apparatus is intended to handle paper rolls of varying lengths and diameters after the main roll wrapping has already been applied in any convenient manner. Of course, rolls requiring wrapper bands and/or end caps and not having the main roll wrapped, may also be handled.

While the machine may be adjusted to handle rolls of different lengths, it usually is set up to handle rolls of a given length in runs or batches in order to avoid unnecessary waste of time in changing the adjustment of the machine for consecutive rolls of different sizes.

10 A roll of paper directed to the machine is held until the cycle of operation permits it to be moved into position for the first operation. At this time, a band of wrapping paper is applied to either or both ends of the roll and intermediately of the ends, as required. The roll is rotated around its longitudinal axis a pre-determined number of times for each band in order to apply 15 the required number of layers of the band. Each end band projects outwardly from its end of the roll. The roll is then ejected from the wrapper portion of the machine and held ready for the crimping stage.

15 When the crimper is ready, the roll is moved into position between two crimper head assemblies which have been moved outwardly away from each other to enable the roll to be moved into place. The crimpers are then moved inwardly against the ends of the roll. Each crimper has a plurality of crimper plates which function somewhat in the same manner as an iris diaphragm. These plates are hingedly mounted on a ring and may be swung towards and away 20 from the ring centre in substantially the same vertical plane. When these plates are swung inwardly, they press or crimp the protruding end of the adjacent wrapper band against the end of the roll. Means may be provided for causing the 25 crimper plates to operate while their head assemblies are still spaced a short distance away from the roll end, and after the wrapping bands have been crimped, the assemblies may be moved towards the roll ends to press the folded bands 30 against the ends of the paper roll, giving them a set.

35 The roll is now ready to have the caps applied to the ends thereof. The roll is moved into position between two capper assemblies which have 40 been moved outwardly to positions which are

spaced from the ends of the roll when the latter is in position between them. The glue is applied to one surface of a cap for each end of the roll, and the cap is moved into position against the inner surface of a capper assembly lying substantially parallel with the adjacent roll end. Then the capper assemblies are moved inwardly of the machine until the caps are pressed firmly against the ends of the roll where they are held for sufficient time to allow the glue to adhere to the crimped bands on the roll ends.

An example of this invention is illustrated in the accompanying drawings, in which,

Figures 1 and 2 constitute a side elevation of the machine from the right to the left thereof, respectively.

Figures 3, 4 and 5 constitute a plan view of the machine from the right thereof, respectively.

Figure 6 is a vertical section taken substantially on line 6—6 of Figure 3.

Figure 7 is a vertical section taken on the line 7—7 of Figure 4.

Figure 8 is a section taken on the line 8—8 of Figure 4, with the crimper plates swung inwardly.

Figure 9 is a vertical section taken on the line 9—9 of Figure 5, and

Figure 10 is a vertical section taken substantially on the line 10—10 of Figure 5.

As this machine is particularly designed for handling rolls of paper which are very heavy, it is shown in a well 10 below the floor level 11. However, it is to be understood that it may be located on a floor with suitable means for lifting the rolls up on to it.

A suitable conveyor 15, see Figures 1 and 3, is provided for moving the paper rolls into position at one end of the machine. Each roll extends longitudinally of the conveyor and it is moved on to a high end of a sloping deck 18 by any suitable mechanism, such as a hydraulically controlled roll kicker 19, the construction of which is well-known in the paper making industry. The roll moves under the force of gravity along the deck until it comes to rest upon a roll stop and loader 22. These devices are also well known in the industry, and they consist mainly of a tiltable plate 23 which is normally set at an angle to prevent a paper roll from moving down the deck. When it is desired to free the roll, the plate is tilted forwardly by suitable pneumatic or hydraulic means 24, linkage 25 and shaft 25a upon which the plate is mounted, to permit the roll resting on it to move down the deck. The deck 18 directs each roll to the band applicator generally designated by the numeral 26, where it comes to rest.

At this point, it may be stated that when the machine is designed for handling rolls of different lengths, the remainder of the machine beyond the band applicator is constructed in two side elements which may be moved towards and away from each other to fit the rolls of different sizes. As each side of the machine is a duplicate of the other, only one side will be generally described for the sake of clarity.

Wrapper band applicator

The applicator 26 appears in Figures 1, 3 and 6, and includes a pair of drums 30 and 31 which extend transversely of the machine. These drums lie in substantially the same horizontal plane and are spaced apart so that when a paper roll moves on to them, it stops moving and is completely supported by them, see Figure 6. Suit-

able means is provided for rotating both of these drums, and this may consist of an electric motor 33 connected directly to a shaft 34 extending from the end of the drum 31, see Figure 3. A sprocket 35 mounted on this shaft is connected by a chain 36 to another sprocket 37 mounted on a shaft 38 extending from the end of the drum 30.

A roll ejector bar 42 extends transversely of the machine between the drums 30 and 31 and is normally positioned below the upper surfaces of these drums, as clearly shown in Figure 6. The upper surface of the ejector bar slopes transversely of the bar so that the rearward edge 43 thereof is slightly higher than the forward edge. With this arrangement, the edge 43 of the ejector is located to one side of the vertical plane passing through the centre of the paper roll resting on the drums 30 and 31 so that upward movement of the ejector will move said roll over the drum 31.

The ejector 42 may be raised and lowered in any desired manner. In this example, hydraulic or pneumatic cylinders 48 are located at opposite sides of the machine and the rams 49 thereof project upwardly and are connected to extensions 50 projecting outwardly from the ends of the ejector.

Two different mechanisms for supplying wrapper bands for the paper rolls are illustrated in the drawings, but it is to be understood that these may be interchanged or the same type of mechanism may be used for applying each band. A carriage 55 is located at each side of the machine for holding the mechanism for supplying the wrapper band to an end of the paper roll. Each carriage is mounted on gear wheels 56 running on racks 57 extending transversely of the machine so that the carriage may be shifted back and forth. The outer gear wheels 56 of the carriage are mounted on a shaft 58 which extends from end to end of the carriage, said shaft having a gear 59 fixedly mounted thereon, see Figures 1 and 3, which is rotated by a pinion 60 mounted on the shaft of an electric motor 61.

The carriage 55 is provided with means for mounting one or more paper rolls 65. The axial length of each roll determines the width of the wrapper band which is applied to the paper roll. A strip of paper from the desired roll 65 extends under an idler 67 and up between a feed roll 68 and the drum 31. This feed roll is carried by supports 69 projecting upwardly from a glue container 70 which is pivotally mounted at 71 on the carriage 55. The pivot point 71 is located at one edge of the bottom of the glue container, and the ram 72 of a hydraulic cylinder 73 is connected to the opposite side of said bottom. The lower end of the cylinder 73 is pivotally mounted at 74 in the carriage. A glue applicator or roll 76 is rotatably mounted in the container 70 and bears against the roll 68.

When the ram 72 of the cylinder 73 is retracted, the feed roll 68 is spaced from the drum 31, and when said ram is moved outwardly, the container 70 pivots about the point 71 to move the feed roll towards the drum, at which time the wrapper band is pressed against said drum.

When it is desired to feed the wrapper band to the paper roll, the drums 30 and 31 are rotated in the direction of the arrows 78, see Figure 6, to turn the paper roll resting on them. The cylinder 73 is operated to cause the feed roll 68 to press the wrapper band against the drum 31 to cause it to move with the latter. The appli-

cator 76 supplies glue to the surface of the feed roll which, in turn, applies the glue to the wrapper band. As the wrapper band passes between the drum 31 and the paper roll, it is pressed on to said roll and the operation continues until the desired number of layers of the wrapper band have been applied to the roll. The drums 30 and 31 are then stopped and the ejector 42 is raised to move the paper roll over the drum 31 on to the high end of a sloping deck 82 located at the discharge side of the band applicator. As the paper roll moves on to this deck, the paper band at the roll end is severed in any suitable manner, such as by a serrated cutter 83 located at the end of the deck facing the drum 31 near each end of the latter.

As stated above, there is a wrapper band feed mechanism at each side of the machine. If it is desired to apply a wrapper band to the paper roll anywhere between the ends thereof, a duplicate of this application mechanism may be used for this purpose. However, in this example, means has been provided for applying a band to the paper roll which is slightly different to that already described. For this purpose, a carriage 87 may be provided beneath the deck 18, said carriage being shiftable laterally of the machine in the same manner as the carriage 55. The carriage 87 is adapted to support a roll of wrapper band stock 89. A strip from this roll extends under an idler roll 91 and over a glue applicator 92 rotatably mounted in a glue container 93, said container being pivotally mounted on the carriage at 94, see Figure 6. The paper strip continues over a finned feed roll 95 also carried by the container 93, and around the drum 30. The ram 96 of a pneumatic or hydraulic cylinder 97 is connected to the container beneath the feed roll and is adapted to move said roll towards and away from the drum 30. When the latter drum is rotated and the feed roll presses the strip of paper against it, the wrapper band is fed to the paper roll. As the paper strip moves over the applicator 92, it receives the glue, and the strip is pressed against the paper roll by the drum. A suitable cutter, such as a serrated cutter 98, extends along the ejector 42 at the edge 43 thereof and facing the drum 31 so that when the ejector is operated to move the roll on to the deck 82, the wrapper band is cut off by the cutter as the roll moves towards the deck.

With this applicator, the paper bands may be applied to either or both ends of the paper roll and to any portion thereof between said ends. If it is desired, the number of layers of the band wrappers may be the same or different at each position. For example, the paper roll may require 7 thicknesses of the wrapper band at one end, 5 thicknesses at the other, and 4 in the middle. In this case, the band applicator drums are started and the band material fed to one end of the paper roll thereon only. When the paper roll has made two complete revolutions, band material is fed to its opposite end, and after one revolution of the paper roll, the centre band is started. At the end of 4 more revolutions of the paper roll, the band drums are stopped.

The applicator may be adjusted to handle paper rolls of different lengths by shifting the carriages 55 laterally of the machine, and the position of the centre wrapper band may be altered by shifting the carriage 87 to the desired position in the machine.

The deck 82 may be of such length that it will hold more than one paper roll at a time. In any

case, a roll stop and loader 102 similar to the stop and loader 22 is provided adjacent the end of this deck remote from the band applicator. This device retains the paper rolls on the deck until one is required for the next operation.

Band crimper assembly

This assembly, see Figures 2, 4, 7 and 8, has a combined stop and unloader 110 located centrally thereof so that a paper roll resting on it is centred on a transverse centre line or axis 111 of the assembly, see Figure 4. This stop and loader may be the same as the stop and loaders 22 and 102, although the one shown in the drawings is slightly different since it is intended to carry the full load of the paper rolls. This device includes a pair of dished supports 114 which are pivotally mounted at one end at 115. The opposite ends of these supports are carried by a horizontal shaft 116 which is pivotally mounted in and carried by the upper end of the ram 117 of a hydraulic or pneumatic cylinder 118. Normally the ends of the supports carried by the ram are lower than their opposite ends so that a paper roll from deck 82 may move on to but not past this device. When it is desired to unload the roll, the cylinder is operated to move its ram outwardly and raise the adjacent ends of the supports to tip the paper roll off the device.

A crimper is located at each side of the machine, and as these are identical, only one will be described in detail. The crimper consists of a relatively long air or hydraulic cylinder 125 having a piston rod 126 extending towards the centre of the machine on the centre line 111 of the crimper assembly. A vertical base plate 127 is mounted on the outer end of the piston rod, said base plate being larger than the end of the largest paper roll to be handled by this apparatus. This base plate has wheels 128 riding on tracks 129 which extend across the machine.

A large gear 134 is rotatably mounted on the piston rod 126 against the outer surface of the base plate. A plurality of pinions 135 are arranged around and mesh with the large gear. Each of these pinions is mounted on a short shaft 136 which extends through the plate 127 and is journalled in a bearing 137 supported by and projecting inwardly from the plate. A crimper plate 140 is mounted on the inner end of each shaft 136. Each crimper plate may be of any desired shape and it is mounted adjacent one end thereof on its shaft. These crimper plates are arranged in a circle around the axis 111 and normally are swung outwardly from said axis, as shown in Figures 2 and 7. Suitable means is provided for rotating the gear 134 to swing the crimper plates inwardly towards said axis. This may be accomplished by one or more small hydraulic or pneumatic cylinders 145 mounted on the outer surface of the gear, see Figure 2. Each cylinder has a piston rod 146 connected at its outer end to a lever 147 projecting inwardly from a pinion 135. In this example, there are two cylinders located near opposite sides of the gear so that one piston rod must be retracted while the other is extended. When the cylinders are operated to move one rod inwardly and the other outwardly, the pinions connected to the levers 147 are rotated, thus causing the large gear 134 to move so that all pinions are rotated at the same time. This swings the crimper plates inwardly or outwardly depending upon the direction of movement of the gear.

Another small hydraulic or pneumatic cylinder

154 is mounted on the inner surface of the base plate 127 centrally thereof and has a piston rod 155 projecting inwardly of the machine, upon the free end of which is mounted a bumper plate 156. The piston rod 155 is normally extended and the bumper plate 156 lies in a plane slightly closer to the centre of the machine than the plane of the crimpler plates 140 as clearly shown in Figure 4. When the rod 155 is retracted, the bumper 156 is withdrawn to the outer side of the plane of the crimpler plates.

As each crimpler plate is only supported adjacent its inner end, at least one roller 159 may be mounted on the base plate 127 immediately behind each crimpler plate when the latter is in its inner position. These rollers may just touch or be just clear of their crimpler plates.

At the time a paper roll is moved on to the stop and unloader 119, the piston rods 126 of the cylinders 125 are retracted so that the crimpler plates 140 are withdrawn clear of the paper roll and said plates are in their outer positions. Then the cylinders 125 are operated to move the crimpler assemblies towards the ends of the paper roll. It will be noted that the bearings 137 are arranged on the base plate 127 so that they clear the periphery of the largest roll to be handled by the machine. When the bumper plate 156 contacts the roll end, the movement of the crimpler assemblies is stopped. The vertical plane of these plates is spaced a little from the roll end, but the plates overlap the portions of the wrapper bands which project from the ends of the roll. The cylinders 145 are actuated to cause the large gears 134 to rotate to swing the crimpler plates 140 inwardly towards the axis of the crimpler centre line. These plates fold the protruding portions of the wrapper bands inwardly of the paper roll against the ends thereof. The pressure in the centre cylinder 154 is released, and the cylinders 125 are actuated to press the crimpler plates firmly against the roll ends, thus setting the crimped wrapper bands. At this time, the rollers 159 prevent the crimpler plates from bending back towards their base plates 127. The cylinders 125 are now actuated to withdraw the crimpler plates from the roll ends, the cylinders 145 are actuated to return the crimpler plates to their outermost positions, and the pressure is returned to the cylinders 154 to move the bumper plate 156 beyond the crimpler plate plane.

The unloader 119 is operated to direct the paper roll on to the high end of a sloping deck 162 which directs the roll to the end cap applicator.

Capper

The deck 162 directs each paper roll on to a combination stop and unloader 165 mounted beneath the transverse centre line 166 of the capper assembly shown in Figures 2, 5, 9 and 10. This device is similar to the combination stop and unloader 119 of the crimpler assembly.

Suitable means is provided for applying glue to one surface of caps 169, moving these caps into position and then applying them to the opposite ends of a paper roll on the stop and unloader 165. For paper rolls, the caps 169 are round and of approximately the same diameter as the roll. A stack of these caps is maintained in a rack 172 on each side of the machine. Each rack is located to one side of the centre line 166 of the capper, as clearly shown in Figure 5, and is mounted on a carriage 173 having wheels 174 riding on tracks 175 which extend longitudinally of the machine. One or more flexible suction

pipes 173 extend from vacuum apparatus, not shown, and each has a nozzle 179 which is directed towards and rests upon the uppermost cap near the edge thereof closest to the centre line 166. Each nozzle is supported by a cross bar 182 which is carried at its opposite ends by a pair of substantially horizontal arms 183 which are pivotally mounted on a shaft 184 which is supported by brackets 185 extending upwardly from the rack. Cam discs 188 are mounted near and below the arms 183 eccentrically on a common shaft 189 which has a sprocket 190 mounted on one end thereof connected by chain 191 to another sprocket 192 mounted on a shaft 193 of an electric motor 194. Each arm has a roller 196 mounted thereon immediately above one of the cams 188 so that when the latter is rotated, it swings the arm upwardly. Each nozzle 179 extends to and is secured to a coupling 200 which is carried by and fixed to the cross bar 182, and the latter is rotatable in bearings 201 on the ends of the arms 183. A pair of L-shaped supports 205 having the upper ends of their vertical sections fixedly secured to the bar 182 at 206, see Figures 5 and 9, carry a transverse shaft 209 at the outer ends of their horizontal sections. A roller 210 is mounted on each end of this shaft beneath a substantially horizontal cam track 211.

With this arrangement, each time the inner ends of the arms 183 are raised by the cams 188, the rollers 210 move in a horizontal direction beneath the cam tracks 211 causing the L-shaped supports 205 to rotate the cross bar 182 at this time. The nozzles 179 are lifted by this action and the rotation of the cross bar causes the lower ends of these nozzles to swing towards the centre line of the capper 166. Suction in the pipe or pipes 173 causes the nozzles to lift the uppermost cap 169 and the swinging movement of the nozzles moves the edge of said cap into the nip between two feed rolls 215 located adjacent said nozzles. The uppermost roll is rotated by the shaft 193 of the motor 194 and presses against the lower roll. These rolls move the cap over a table 216 to a glue applicator 217. Normally when applying glue to a surface of an article, the article is moved between a pressure roller and a glue applicator roller. However, in this case, each cap 169 is circular in shape so that for a large percentage of the time the pressure roller will be bearing against the glue applicator roller and would become covered with glue in a very short time.

To avoid this, a glue applicator roll 220 is used having a plurality of spaced grooves 221 formed in the periphery thereof. This roller rotates in a container 222 which holds a quantity of glue. The pressure roller is in the form of a plurality of spaced discs 225 mounted on a shaft 226, each disc being located above a groove 221 in the roller 220, see Figures 5 and 10. There is sufficient space between the discs and the periphery of the roller to enable a cap to pass therebetween. A notched scraper 228 has fingers 229 fitting into the grooves 221 to keep the latter cleared of glue. The main portion of the scraper controls the thickness of the layer of glue on the periphery of the applicator roller. The disc shaft 226 is rotated in any convenient manner. In this example, a sprocket 232 mounted on one end of the shaft 193 on which the upper pressure roll 215 is mounted, is connected by a chain 234 to another sprocket 235 mounted on the shaft 226. A gear 236 mounted on shaft 226 meshes with a gear 237 mounted on a shaft 238 projecting from

the adjacent end of the roll 220, see Figure 5, so that the latter roll rotates with the pressure roll discs 225.

A cap passing between the roller 220 and the discs 225 has a coating of glue applied to its lower surface, excepting the portions thereof passing over the roller grooves. Each cap is received by a series of rolls 240, each of which consists of a plurality of spaced discs 241 mounted on a shaft 242. Each of these shafts has a sprocket 243 connected by a common chain 244 to a single sprocket 245 mounted on the shaft 238. The discs 241 are in line with the grooves 221 of the applicator roll 220, so that the portions of the lower surfaces of each cap which are devoid of glue come into contact with said discs. If desired, suitable scrapers may be provided for removing any glue which may adhere to the discs. A plurality of fingers 248 project upwardly adjacent the edge of the table formed by the discs 241 remote from the glue applicator.

It will be noted that all the mechanism described so far for handling the caps 169 is mounted on the carriage 173. Suitable means illustrated at 250 is provided for shifting the carriage longitudinally of the machine. The reason for this is that it is necessary to have the centre of each cap resting on the discs 241 lying in the vertical plane of the centre line 166 of the capper. As caps of different sizes are used in this machine, the carriage 173 is shifted longitudinally of the machine to position the different sized caps in the right place.

A relatively long air or hydraulic cylinder 265 is mounted on the outer side of each table made up of discs 241 and on the centre line 166 of the capper. A piston rod 266 extends inwardly from the cylinder towards the centre of the machine and has a vertical platen 267 mounted on its inner end. This platen is larger than the end of the largest roll to be handled by the machine, and it has wheels 268 riding on transverse tracks 269 so that the platen may be moved towards and away from the centre of the machine by the piston rod.

A hollow arm 274, see Figures 9 and 10, is mounted in the platen and has its face flush with the inner face 275 of the latter. A plurality of openings 276 are formed in the inner face of the hollow arm 274. This arm is carried by levers 279 at its lower end which are pivotally mounted on a shaft 280 carried by bracket 281 extending downwardly from the platen. The opposite end of one of these levers is connected to the piston rod 284 of an air or hydraulic cylinder 285 pivotally mounted on the back of the platen by means of a bracket 286. The arm 274 normally lies within the platen in a substantially vertical plane, and when the piston rod 284 is retracted, this arm is moved into a substantially horizontal position, as shown in dotted lines in Figure 10, immediately above the discs 241. Actually, at this time, the hollow arm engages a cap 169 resting on said discs. A suction hose 290 is connected to the bottom of the arm 274, said hose extending to suitable vacuum apparatus, not shown.

In operation, the cams 188 raise the arms 183 to lift the uppermost cap 169 from the pile and insert the edge thereof between the pressure rollers 215. These move the cap to the glue applicator, and the power driven discs 225 and roll 220 thereof move the cap with its layer of glue on to the table of discs 241, the pins 248 stopping the cap in the correct position. When

a roll of paper reaches the stop and unloader 165, the platens 267 are drawn outwardly as far as possible. The cylinders 285 of the platens are actuated to cause the hollow arms 274 to move down on to the caps in position on the table discs in front of them. When these arms are returned to their normal vertical positions, the suction therein lifts the caps with them. Then the cylinders 265 are actuated to move the platens inwardly against the ends of the paper roll to press the caps against the crimped wrapper band. Pressure is maintained long enough to ensure the caps remaining in place, and then the platens are withdrawn to their outermost positions. The unloader 165 is then actuated to direct the paper roll on to the upper end of a sloping deck 291 which guides it away from the machine.

Controls and general operation

In order to co-ordinate all the component parts of this machine, a system of inter-locking controls is installed. These controls are all standard equipment and need not be described in detail herein. It has been found that the band application is the slowest operation so that all other parts of the equipment are timed from the band applicator. The number of revolutions made by the paper roll when the band or bands are being put on and the length of time the roll remains in this section of the machine may be controlled by an operator. However, the operation of the remainder of the machine will be completely automatic. Paper rolls are supplied to the machine by the conveyor 15. At the right time, the roll kicker 18 is operated to move each roll on to the sloping deck 18. The stop 22 holds the roll on the deck until the band applicator is ready to receive it. Then the loader 22 is operated to free the roll to allow it to move on to the drums 30 and 31 of the band applicator. At this point, the required bands are applied to the roll at either or both ends and/or any desired point between said ends. When this is completed, the ejector 42 is operated to move the roll on to the sloping deck 82 where it is retained by the stop 102.

When the loader 102 moves a paper roll on to the stop 110 of the crimper, cylinders 125 are actuated to move the crimper assemblies towards the roll ends, and the central cylinders 154 are operated to extend the bumper plates 156 beyond the planes of the crimper plates. As soon as the bumper plates engage the ends of the roll, the crimper plates are swung inwardly to crimp the wrapper bands over the roll ends. Then the bumper plates 156 are withdrawn to permit the crimper plates to press against and set the crimped bands. As the crimper assemblies are withdrawn from the roll, the crimper plates are returned to their outermost positions. The unloader 110 discharges the roll from the crimper and said roll moves down the deck 162 on to the stop 165. Just prior to this, caps had been moved through the glue applicator and picked up by hollow arms 274 of the platens 267, the latter being in their outermost positions. The cylinders 265 are actuated to move the platens against the roll ends. The suction is cut off from the hollow arms and, after a predetermined time, the platens are withdrawn to their outermost positions, by which time new caps are resting on the tables of discs 241. The unloader 165 is now raised to discharge the roll on to deck 291 and out of the machine.

What I claim as my invention is:

1. In a roll wrapping apparatus, apparatus for crimping a band wound around an end of a roll and projecting outwardly therefrom, comprising supporting means for a roll, a vertical base to one side of the supporting means, means for moving the base towards and away from the end of a supported roll with the band thereon, a plurality of flat wide crimper plates pivotally mounted adjacent an edge thereof on a face of the base substantially in a common plane and arranged around a common centre, means for stopping the base with the plates spaced a little beyond the roll end, said plates being normally positioned outside the band, means for rotating the plates towards the common centre to crimp the projecting part of the band against the roll end, a roller on the base immediately behind each plate when the latter is in its innermost position, said plates substantially covering the roll end when in their innermost positions, and means for releasing the base stopping means to permit the plates to be moved against the crimped band to press and set the latter against the roll end, said rollers acting as bearings behind the plates to prevent the latter from being bent out of shape when pressing and setting the band.

2. In roll wrapping apparatus, apparatus for crimping a band wound around an end of a roll and projecting outwardly therefrom, comprising supporting means for a roll, a base to one side of the supporting means, means for moving the base towards and away from the end of a supported roll with the band thereon, a plurality of flat wide crimper plates pivotally mounted on the base substantially in a common plane and arranged around a common centre, means for stopping the base with the plates spaced a little beyond the roll end, said plates being normally positioned outside the band, means for rotating the plates towards the common centre to crimp the projecting part of the band against the roll end, said plates substantially covering the roll end when in their innermost positions, and means for releasing the base stopping means to permit the plates to be moved against the crimped band to press and set the latter against the roll end.

3. In roll wrapping apparatus, apparatus for crimping a band wound around an end of a roll and projecting outwardly therefrom, comprising supporting means for a roll, a base to one side of the supporting means, means for moving the base towards and away from the end of a supported roll with the band thereon, a plurality of crimper plates pivotally mounted on the base substantially in a common plane and arranged around a common centre, a cylinder projecting outwardly from the base within the circle of crimper plates, a piston rod projecting from the cylinder, a bumper plate carried by the piston rod, said bumper plate being positioned beyond the plane of the crimper plates when the piston rod is extended to engage the end of a roll with a band thereon to stop the crimper plates a little beyond said end when they are being moved towards the latter, said crimper plates being normally positioned outside the band, and means for rotating the plates towards the common centre to crimp the projecting part of the band against the roll end, and means for operating the cylinder to withdraw the bumper plate to the plane of the crimper plates thereby permitting said plates to press the crimped band against the roll end.

4. In roll wrapping apparatus, apparatus for applying caps to the ends of rolls, comprising supporting means for a roll, a platen in a vertical plane substantially parallel with the end of a supported roll, means for moving the platen towards and away from the roll end, a table for supporting a cap to be applied to the roll end, and suction means for lifting the cap from the table into the plane of the platen, said platen being moved to press the cap against the roll end.

5. In roll wrapping apparatus, apparatus for applying caps to the ends of rolls, comprising supporting means for a roll, a platen in a plane substantially parallel with the end of a supported roll, means for moving the platen towards and away from the roll end, a table between the platen when in its outermost position and the roll end, said table being located to one side of the path of movement of the platen and being adapted to support a cap with glue on the under surface thereof, an arm hingedly mounted on the platen normally lying in the plane of the latter, means for moving the arm against the outer surface of the cap, and suction means associated with the arm for lifting the cap when said arm is returned to its normal position, said platen being moved to press the glue surface of the cap against the roll end.

6. In roll wrapping apparatus, apparatus for applying caps to the ends of rolls, comprising supporting means for a roll, a platen in a plane substantially parallel with the end of a supported roll, means for moving the platen towards and away from the roll end, a table consisting of a plurality of parallel rolls between the platen when in its outermost position and the roll end, each roll being made up of a plurality of spaced discs mounted on a shaft and said table being located to one side of the path of movement of the platen, and said roll discs supporting a cap with glue on the under surface thereof, an arm hingedly mounted on the platen normally lying in the plane of the latter, means for moving the arm against the outer surface of the cap, and suction means associated with the arm for lifting the cap when said arm is returned to its normal position, said platen being moved to press the glue surface of the cap against the roll end.

7. In roll wrapping apparatus, apparatus for applying caps to the ends of rolls, comprising supporting means for a roll, a platen in a plane substantially parallel with the end of a supported roll, means for moving the platen towards and away from the roll end, a table for supporting a cap to be applied to the roll end, a hollow arm hingedly mounted adjacent one end on the platen normally lying in the plane of the latter, said arm having a plurality of openings in its outer surface near the outer end thereof, means for creating a vacuum within the arm, and means for moving the arm against a cap on the table and returning the arm to its normal position, the vacuum in the arm causing sufficient suction to lift the cap with the arm, and said platen being moved to press the cap against the roll end at which time the vacuum in the arm is cut off.

8. In roll wrapping apparatus, apparatus for applying caps to the ends of rolls, comprising supporting means for a roll, a rack for supporting a pile of caps, a pair of feed rolls beside the rack, suction means for lifting the uppermost cap and moving it between the feed rolls, a glue applicator having a roll over which the cap from the feed rolls is moved, a table for receiving the glued cap,

and means for picking the cap up from the table and pressing it against an end of the roll.

9. In roll wrapping apparatus, apparatus for applying caps to the ends of rolls, comprising supporting means for a roll, a rack for supporting a pile of caps, a pair of feed rolls, suction means for lifting the uppermost cap and moving it between the feed rolls, a glue applicator including a roll having a plurality of spaced grooves in its periphery, a pressure roller for the applicator roll consisting of a plurality of spaced discs mounted on a shaft, there being a disc over each roll groove, a table for receiving the glued cap, and means for picking the cap up from the table and pressing it against an end of the roll.

10. In roll wrapping apparatus, apparatus for applying caps to the ends of rolls, comprising supporting means for a roll, a rack for supporting a pile of caps, a pair of feed rolls, suction means for lifting the uppermost cap and moving it between the feed rolls, a glue applicator including a roll having a plurality of spaced grooves in its periphery, a pressure roller for the applicator roll consisting of a plurality of spaced discs mounted on a shaft, there being a disc over each roll groove, a table for receiving the glued cap consisting of a plurality of parallel rolls, each roll being made up of a plurality of spaced discs mounted on a shaft, and each of said table discs being in line with a pressure roller disc, and means for picking the cap up from the table and pressing it against an end of the roll.

11. In roll wrapping apparatus, apparatus for applying caps to the ends of rolls, comprising supporting means for a roll, a rack for supporting a pile of caps, a pair of feed rolls, suction means for lifting the uppermost cap and moving it between the feed rolls, a glue applicator having a roll over which the cap from the feed rolls is moved, a table for receiving the glued cap, a platen in a plane substantially parallel with the end of a supported roll, means for moving the platen towards and away from the roll end, and suction means for moving the cap from the table into the plane of the platen, said platen being moved to press the cap against the roll end.

12. In a roll wrapping apparatus, apparatus for applying caps to the ends of rolls, comprising supporting means for a roll, a rack for supporting a pile of caps, a pair of feed rolls, suction means for lifting the uppermost cap and moving it between the feed rolls, a glue applicator having a roll over which the cap from the feed rolls is moved, a table for receiving the glued cap, a platen in a plane substantially parallel with the end of a supported roll, means for moving the platen towards and away from the roll end, said table being between the platen when in its outermost position and the roll end to one side of the path of movement of the platen, an arm hingedly mounted on the platen normally lying in the plane of the latter, means for moving the arm against the outer surface of the cap, and suction means associated with the arm for lifting the cap when said arm is returned to its normal position, said platen being moved to press the glue surface of the cap against the roll end.

13. Roll wrapping apparatus comprising supporting means for a roll having a band wound around an end thereof and projecting outwardly from said end, a base positioned to one side of the supporting means, a plurality of flat wide crimper plates pivotally mounted on the base substantially in a common plane and arranged around a common centre, said plane being paral-

lel with and spaced a little beyond the end of the roll with the band thereon and said plates being normally positioned outside the band, means for rotating the plates towards the common centre to crimp the projecting part of the band against the roll end, said plates substantially covering the roll end when in their innermost positions, means for moving the plates against the roll end to press and set the crimper band against the latter, supporting means spaced from the first supporting means for receiving the roll when released from the latter, a platen in a plane substantially parallel with the end of the roll on the second supporting means having the crimped band thereon, means for moving the platen towards and away from the roll end, a table for supporting a cap to be applied to the roll end, and suction means for lifting the cap from the table into the plane of the platen, said platen being moved to press the cap against the roll end.

14. Roll wrapping apparatus for rolls having a band wound around and projecting from an end thereof, comprising supporting means for a roll, a base positioned to one side of the supporting means, a plurality of crimper plates pivotally mounted on the base substantially in a common plane and arranged around a common centre, said plane being parallel with and spaced a little beyond the banded end of a roll on the supporting means and said plates being normally positioned outside the band, means for rotating the plates towards the common centre to crimp the projecting part of the band against the roll end, supporting means for the roll when released from the latter, a platen to one side of the second supporting means and in a plane substantially parallel with the crimped end of a roll on said second supporting means, means for moving the platen towards and away from the roll end, a table between the platen when in its outermost position and the roll end, said table being located to one side of the path of movement of the platen and being adapted to support a cap with glue on the under surface thereof, an arm hingedly mounted on the platen normally lying in the plane of the latter, means for moving the arm against the outer surface of the cap, and suction means associated with the arm for lifting the cap when said arm is returned to its normal position, said platen being moved to press the glue surface of the cap against the roll end.

15. Roll wrapping apparatus for rolls having a band wound around and projecting from an end thereof, comprising supporting means for a roll, a base positioned to one side of the supporting means, a plurality of crimper plates pivotally mounted on the base substantially in a common plane and arranged around a common centre, said plane being parallel with and spaced a little beyond the banded end of a roll on the supporting means and said plates being normally positioned outside the band, means for rotating the plates towards the common centre to crimp the projecting part of the band against the roll end, supporting means for the roll when released from the latter, a platen to one side of the second supporting means and in a plane substantially parallel with the crimped end of the roll on said second supporting means, means for moving the platen towards and away from the roll end, a table for supporting a cap to be applied to the roll end, and suction means for moving the cap from the table into the plane of the platen,

said platen being moved to press the cap against the roll end.

16. Roll wrapping apparatus for rolls having a band wound around and projecting from an end thereof, comprising supporting means for a roll, a base positioned to one side of the supporting means, a plurality of crimper plates pivotally mounted on the base substantially in a common plane and arranged around a common centre, said plane being parallel with and spaced a little beyond the banded end of the roll on the second supporting means and said plates being normally positioned outside the band, means for rotating the plates towards the common centre to crimp the projecting part of the band against the roll end, means for moving the plates towards the roll to press the crimped band against the roll end, supporting means for the roll when released from the latter, a platen to one side of the second supporting means and in a plane substantially parallel with the crimped end of the roll on said second supporting means, means for moving the platen towards and away from the roll end, a table between the platen when in its outermost position and the roll end, said table being located to one side of the path of movement of the platen and being adapted to support a cap with glue on the under surface thereof, an arm hingedly mounted on the platen normally lying in the plane of the latter, means for moving the arm against the outer surface of the cap, and suction means associated with the arm for lifting the cap when said arm is returned to its normal position, said platen being moved to press the glue surface of the cap against the roll end.

17. Roll wrapping apparatus comprising supporting means for rotatably carrying a roll, means for rotating the roll about its longitudinal axis, feeding means for directing a wrapper band to the roll, said band being wrapped around an end of the roll during rotation thereof and projecting outwardly from said end, supporting means spaced from the first supporting means for receiving the roll from the latter, a base positioned to one side of the second supporting means, a plurality of crimper plates pivotally mounted on the base substantially in a common plane and arranged around a common centre, said plane being parallel with and spaced a little beyond the banded end of the roll on the second supporting means and said plates being normally positioned outside the band, means for rotating the plates towards the common centre to crimp the projecting part of the band against the roll end, supporting means spaced from the second supporting means for receiving the roll when released from the latter, a platen to one side of the third supporting means and in a plane substantially parallel with the crimped end of the roll on said third supporting means, means for moving the platen towards and away from the roll end, a table for supporting a cap to be applied to the roll end, and suction means for moving the cap from the table into the plane of the platen, said platen being moved to press the cap against the roll end.

18. Roll wrapping apparatus comprising supporting means for rotatably carrying a roll, means for rotating the roll about its longitudinal axis, feeding means for directing a wrapper band to the roll, said band being wrapped around an end of the roll during rotation thereof and projecting outwardly from said end, supporting means spaced from the first supporting means for receiving the roll from the latter, a base positioned

to one side of the second supporting means, a plurality of crimper plates pivotally mounted on the base substantially in a common plane and arranged around a common centre, said plane being parallel with and spaced a little beyond the banded end of the roll on the second supporting means and said plates being normally positioned outside the band, means for rotating the plates towards the common centre to crimp the projecting part of the band against the roll end, supporting means spaced from the second supporting means for receiving the roll when released from the latter, a platen to one side of the third supporting means and in a plane substantially parallel with the crimped end of the roll on said third supporting means, means for moving the platen towards and away from the roll end, a table between the platen when in its outermost position and the roll end, said table being located to one side of the path of movement of the platen and being adapted to support a cap with glue on the under surface thereof, an arm hingedly mounted on the platen normally lying in the plane of the latter, means for moving the arm against the outer surface of the cap, and suction means associated with the arm for lifting the cap when said arm is returned to its normal position, said platen being moved to press the glue surface of the cap against the roll end.

19. Roll wrapping apparatus comprising supporting means for rotatably carrying a roll, means for rotating the roll about its longitudinal axis, feeding means for directing a wrapper band to the roll, said band being wrapped around an end of the roll during rotation thereof and projecting outwardly from said end, supporting means spaced from the first supporting means for receiving the roll from the latter, a base positioned to one side of the second supporting means, a plurality of crimper plates pivotally mounted on the base substantially in a common plane and arranged around a common centre, said plane being parallel with and spaced a little beyond the banded end of the roll on the second supporting means and said plates being normally positioned outside the band, means for rotating the plates towards the common centre to crimp the projecting part of the band against the roll end, means for moving the plates towards the roll to press the crimped band against the roll end, supporting means spaced from the second supporting means for receiving the roll when released from the latter, a platen to one side of the third supporting means and in a plane substantially parallel with the crimped end of the roll on said third supporting means, means for moving the platen towards and away from the roll end, a table for supporting a cap to be applied to the roll end, and suction means for moving the cap from the table into the plane of the platen, said platen being moved to press the cap against the roll end.

20. Roll wrapping apparatus comprising supporting means for rotatably carrying a roll, means for rotating the roll about its longitudinal axis, feeding means for directing a wrapper band to the roll, said band being wrapped around an end of the roll during rotation thereof and projecting outwardly from said end, supporting means spaced from the first supporting means for receiving the roll from the latter, a base positioned to one side of the second supporting means, a plurality of crimper plates pivotally mounted on the base substantially in a common

plane and arranged around a common centre, said plane being parallel with and spaced a little beyond the banded end of the roll with the band thereon and said plates being normally positioned outside the band, means for rotating the plates towards the common centre to crimp the projecting part of the band against the roll end, means for moving the plates towards the roll to press the crimped band against the roll end, supporting means spaced from the second supporting means for receiving the roll when released from the latter, a platen to one side of the third supporting means and in a plane substantially parallel with the crimped end of a roll on said third supporting means, means for moving the platen towards and away from the roll end, a table between the platen when in its outermost position and the roll end, said table being located to one side of the path of movement of the platen and being adapted to support a cap with glue on the under surface thereof, an arm hingedly mounted on the platen normally lying in the plane of the latter, means for moving the arm against the outer surface of the cap, and suction means associated with the arm for lifting the cap when said arm is returned to its normal position, said platen being moved to press the glue surface of the cap against the roll end.

21. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, a plurality of independent feeding means for directing wrapper bands to the roll at different points throughout its length, said bands being wrapped around the roll during rotation thereof, and separate control means for each feeding means, whereby a wrapper band may be applied to the roll by any feeding means independently of the other feeding means.

22. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, a plurality of independent feeding means for directing wrapper bands to the roll at different points throughout its length, at least one of said feeding means being positioned adjacent an end of the roll so that a part of the band fed therefrom projects beyond said end, and said bands being wrapped around the roll during rotation thereof, and separate control means for each feeding means, whereby a wrapper band may be applied to the roll by any feeding means independently of the other feeding means.

23. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, a plurality of spaced carriages adjacent the drums mounted for movement longitudinally of the latter, means for supporting a relatively narrow band roll on each carriage, feeding means on each carriage for directing a wrapper band from the band roll on said carriage to the roll on the drums, each band being wrapped around the roll during rotation thereof by the drums, and separate control means for each feeding means whereby a wrapper

band from each band roll may be applied to the roll on the drums independently of the other band rolls.

24. Roll wrapping apparatus as claimed in claim 5 including means for moving each carriage longitudinally of the drums independently of the other carriages.

25. Roll wrapping apparatus comprising a pair of spaced-apart drums extending parallel to each other, said drums supporting a roll placed thereon and extending longitudinally thereof, means for rotating a drum to turn the roll about its longitudinal axis, feeding means for directing a wrapper band to the roll, said band being wrapped around the roll during rotation thereof, ejecting means located between the drums for rolling the roll over one of the latter to discharge it therefrom, a cutter supported adjacent and extending longitudinally of the drum over which the rolls are discharged, and another cutter extending along the ejecting means, said cutters severing the band wrapped around the roll as the latter is ejected.

26. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, a plurality of independent feeding means for directing wrapper bands to the roll at different points throughout its length, said bands being wrapped around the roll during rotation thereof, ejecting means located between the drums for rolling the roll over one of the latter to discharge it therefrom, a cutter supported adjacent and extending longitudinally of the drum over which the rolls are discharged, and another cutter extending along the ejecting means, said cutters severing the bands wrapped around the roll as the latter is ejected.

27. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, a plurality of independent feeding means for directing wrapper bands to the roll at different points throughout its length, said bands being wrapped around the roll during rotation thereof, and at least one band projecting outwardly from an end of the roll, separate control means for each feeding means, supporting means spaced from the drums for receiving the roll from the latter, a base to one side of the supporting means, a plurality of crimpler plates pivotally mounted on the base substantially in a common plane and arranged around a common centre, said plane being parallel with and spaced a little beyond the end of the roll with the band thereon and said plates being normally positioned outside the band, and means for rotating the plates towards the common centre to crimp the projecting part of the band against the roll end.

28. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, a plurality of independent feeding means for directing wrapper bands to the roll at different points throughout its length, said bands being wrapped around the roll during rotation thereof, and at

least one band projecting outwardly from an end of the roll, separate control means spaced from the drums for receiving the roll from the latter, a base to one side of the supporting means, a plurality of flat wide crimper plates pivotally mounted on the base substantially in a common plane and arranged around a common centre, means for stopping the base with the plates spaced a little beyond the roll end, said plates being normally positioned outside the band, means for rotating the plates towards the common centre to crimp the projecting part of the band against the roll end, said plates substantially covering the roll end when in their innermost positions, and means for releasing the base stopping means to permit the plates to be moved against the crimped band to press and set the latter against the roll end.

29. Roll wrapping apparatus comprising a pair of spaced-apart drums extending parallel to each other, said drums supporting a roll placed thereon and extending longitudinally thereof, means for rotating a drum to turn the roll about its longitudinal axis, feeding means for directing a wrapper band to the roll, said band being wrapped around the roll during rotation thereof, ejecting means located between the drums for rolling the roll over one of the latter to discharge it from the drums, a cutter supported adjacent and extending longitudinally of the drum over which the rolls are discharged, and another cutter extending along the ejecting means, said cutters severing the band wrapped around the roll as the latter is ejected, supporting means spaced from the drums for receiving the roll from the latter, a base to one side of the supporting means, a plurality of crimper plates pivotally mounted on the base substantially in a common plane and arranged around a common centre, said plane being parallel with and spaced a little beyond the end of the roll with the band thereon and said plates being normally positioned outside the band, and means for rotating the plates towards the common centre to crimp the projecting part of the band against the roll end.

30. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, a plurality of independent feeding means for directing wrapper bands to the roll at different points throughout its length, said bands being wrapped around the roll during rotation thereof, ejecting means located between the drums for rolling the roll over one of the latter to discharge it therefrom, a cutter supported adjacent and extending longitudinally of the drum over which the rolls are discharged, another cutter extending along the ejecting means, said cutter severing the bands wrapped around the roll as the latter is ejected, supporting means spaced from the drums for receiving the roll from the latter, a base to one side of the supporting means, a plurality of crimper plates pivotally mounted on the base substantially in a common plane and arranged around a common centre, said plane being parallel with and spaced a little beyond the end of the roll with the band thereon and said plates being normally positioned outside the band, and means for rotating the plates towards the common centre to crimp the projecting part of the band against the roll end.

31. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, means for supporting a relatively narrow band roll adjacent the drums, a feed roll movably mounted near and parallel with one of the drums, a strip from the band roll extending between the feed roll and said drum and the feed roll being movable towards the drum to press the strip against the latter, a glue applicator roll continuously bearing against the feed roll and movable therewith, a container for supplying glue to the applicator roll, said feed roll transferring glue from the applicator roll to a surface of the strip, means for moving the feed roll to press the glue-free surface of the strip against the drum to draw the former off the band roll, the glue side of the strip being pressed by said drum against the paper roll on the drums causing the strip to encircle the latter roll during rotation thereof.

32. Roll wrapping apparatus comprising a pair of spaced-apart drums extending parallel to each other, said drums being capable of supporting a roll placed thereon and extending longitudinally thereof, means for rotating a drum to turn a roll thereon about its longitudinal axis, means for supporting a relatively narrow band roll adjacent the drums, a feed roll movably mounted near and parallel with one of the drums, a strip from the band roll extending between the feed roll and said drum and the feed roll being movable towards the drum to press the strip against the latter, a glue applicator roll over which the strip extends before reaching the feed roll, a container for supplying glue to the applicator roll to be transferred to a surface of the strip, means for moving the feed roll to press the glue-free surface of the strip against the drum to draw the former off the band roll, the glue side of the strip being pressed by said drum against the paper roll on the drums causing the strip to encircle the latter roll during rotation thereof.

33. In roll wrapping apparatus, apparatus for applying caps to the ends of rolls, comprising supporting means for a roll, supporting means for a pile of caps, a nozzle connected to vacuum means and normally resting on the uppermost cap, a table adjacent the supporting means, feeding means for the table positioned near the nozzle, means for raising the nozzle to move the uppermost cap to the feeding means, said feeding means directing the cap on to the table, and means for picking the cap up from the table and pressing it against an end of the roll.

34. In roll wrapping apparatus, apparatus for applying caps to the ends of rolls, comprising supporting means for a roll, supporting means for a pile of caps, a nozzle connected to vacuum means and normally resting on the uppermost cap, a table adjacent the supporting means, feeding means for the table positioned near the nozzle, means for raising the nozzle to move the uppermost cap to the feeding means, said feeding means directing the cap on to the table, a glue applicator having a roll over which the cap is moved by the feeding means on its way to the table, and means for picking the cap up from the table and pressing the glued surface thereof against an end of the roll.

35. In roll wrapping apparatus, apparatus for applying caps to the ends of rolls, comprising supporting means for a roll, supporting means

for a pile of caps, feeding means for receiving the caps one at a time, a rotatable shaft mounted between the caps and the feeding means, a nozzle secured to the shaft normally resting on the uppermost cap, said nozzle being connected to vacuum means, means for intermittently raising and rotating the shaft to move the uppermost cap to the feeding means, a table for receiving the cap from the feeding means, and means for picking the cap up from the table and pressing it against an end of the roll.

36. In roll wrapping apparatus, apparatus for applying caps to the ends of rolls, comprising supporting means for a roll, a rack for supporting a pile of caps, a pair of feed rolls beside the rack, a pair of spaced, substantially horizontal arms adjacent the rack, said arms being pivotally mounted at one end, a shaft journalled in the opposite ends of the arms in a plane above the stack near one side thereof, a nozzle secured to the shaft normally resting on the uppermost cap, said nozzle being connected to vacuum means, means for intermittently raising the shaft ends of the arms to lift the uppermost cap, means pivoting the shaft during said arm movement to move the cap between the feed rolls, a table for receiving the cap from the feed rolls, and means for picking the cap up from the table and pressing it against an end of the roll.

37. In roll wrapping apparatus, apparatus for applying caps to the ends of rolls, comprising

supporting means for a roll, a rack for supporting a pile of caps, a pair of feed rolls beside the rack, a pair of spaced, substantially horizontal arms adjacent the rack, said arms being pivotally mounted at one end, a shaft journalled in the opposite ends of the arms in a plane above the stack near one side thereof, a nozzle secured to the shaft normally resting on the uppermost cap, said nozzle being connected to vacuum means, means for intermittently raising the shaft ends of the arms to lift the uppermost cap, means pivoting the shaft during said arm movement to move the cap between the feed rolls, a glue applicator having a roll over which the cap from the feed rolls is moved, a table for receiving the glued cap, and means for picking the cap up from the table and pressing it against an end of the roll.
